LOCKING TONGUE FOR KNOCKDOWN FURNITURE

Filed June 9, 1923

Patented May 12, 1925.

1,537,459

UNITED STATES PATENT OFFICE.

CHARLES PETER CAMPBELL, OF ORILLIA, ONTARIO, CANADA.

LOCKING TONGUE FOR KNOCKDOWN FURNITURE.

Application filed June 9, 1923, Serial No. 644,410.

To all whom it may concern:

Be it known that I, CHARLES PETER CAMPBELL, of the town of Orillia, in the county of Simcoe, in the Province of Ontario, Canada, have invented certain new and useful Improvements in Locking Tongues for Knock-down Furniture, of which the following is the specification.

My invention relates to improvements in locking tongue construction for knock-down furniture, and the object of the invention is to devise a locking tongue and coacting parts which may be simply and cheaply constructed and yet be efficient in operation, and it consists essentially of the arrangement and construction of parts hereinafter more fully explained.

Fig. 1 is a sectional view of two wall members set at right angles one to the other, and my locking tongue connection applied thereto.

Fig. 2 is a vertical section taken through Fig. 1, showing the locking tongue in full and the wall members in section.

Fig. 3 is a plan view of the blank out of which my locking tongue is formed.

Fig. 4 is a perspective view of the blank shown in Fig. 3 partially bent up to form a locking tongue.

Fig. 5 is a perspective detail of the end cap forming the head of the locking tongue.

Fig. 6 is a perspective view of a portion of the keeper bar showing one of the keeper slots therein.

Figs. 7 to 12 show a modified construction adapted to lock the walls of a drawer together.

Fig. 7^x is a plan view showing the parts illustrated in Figs. 7 and 8.

In the drawings like characters of reference indicate corresponding parts in each figure.

1 indicates a corner post of a piece of furniture. 3 indicates a side wall connected to the post 1, the vertical edge of the wall being secured in vertical grooves 4 formed in the post 1. The post 1 is recessed as indicated at 5.

7 is a wall which is to be detachably connected to the post 1. 8 is a channel bar provided with a slotted opening 9, the side edges of which converge downward. The lower portion of the slot 9 is provided with a slit extension 10.

11 is my locking tongue. Each locking

tongue is formed from a sheet metal blank, as illustrated in Fig. 3.

The body of the blank is in the form of a strip of metal, the ends of which are provided with out-turned portions 13 and 14, the end edges of which incline downward in a converging direction when the blanks formed by the end portions 13 and 14 are turned outward, as illustrated in Fig. 4. The body of the blank 12 is bent upon itself centrally as indicated at 15, and by the dotted line 15^x, Fig. 3. The upper edge of the blank 12 is provided with extensions 16 and 17, the inner ends of which are separated from each other by the slit opening 18 which is in vertical alignment with the dotted line 15^x, (see Fig. 3). When the blank 12 is formed into the locking tongue, the portions 16 and 17 are bent outward forming horizontal flanges as indicated in Fig. 4. When the portions 12^x and 12^y of the blank 12 are bent together into a parallel position, the free ends of the blank formed by the out-turned portions 13 and 14 are secured together by means of the securing cap 21 forming a head, the construction of which I will later describe.

Each corner of the wall 7 is provided with a saw cut slit indicated at 29, into which the locking tongue 11 fits. Although I have described the tongue 11 as secured in this way, it will of course be understood that it may be secured to the wall 7 in any other way desired.

When my device is applied to a bureau drawer, it is preferably constructed as follows:

35 and 36 are two adjacent walls of a bureau drawer. The edge of the wall 35 is provided with a recess 38, and the adjacent wall with a recess 40.

42 is a channel piece secured in the recess 38 in proximity to the top and bottom wall. Each channel piece 42 is provided with a downwardly slit opening 44 having open upper ends. 45 is the locking tongue, the edge of which and the head of the locking tongue 11 are similar in construction and provided with a cap 21, as illustrated in Fig. 5. The body of the locking tongue 45, however, is formed by a vertical sheet metal bar portion bent upon itself on a vertical line, as indicated at 46, the upper and lower ends of the body of the tongue 45 being so formed that when the portions of the body 110

are bent together, the out-turned extensions 47 and 48 are provided, (see Figs. 9 and 11).

The outer ends of the extensions 47 and 48 are constructed in a similar manner to that illustrated in Figs. 5 and 6, thereby forming locking heads which engage in the channel portions 42 by slipping that portion of the tongue 45 adjacent to the extensions 47 and 48 vertically downward into the slit 10 openings 44, thereby securely holding the end walls together.

I will now describe the construction of the cap 21 by which the free ends of the portions 12^x and 12° of the locking tongue 11 provided with the out-turned portions 13 and 14 are secured together, and also the corresponding portions of the locking tongue 45 provided with the out-turned portions 47 and 48.

20 The front wall of the cap 21 is provided with downwardly inclined converging side edges corresponding to the inclined edges 13 and 14 in one case, and the inclined edges of the portions 47 and 48 in the other case.

25 Each side edge of the body of the cap 21 is provided with inturned portions 22 and 23 terminating in portions 24 and 25 turned inward at right angles to the portions 22 and 23 so that when the portions 13 and 14 are

30 brought together, the cap above described will slip upward thereonto. The front portion of the cap bears against the outer faces of the portions 13 and 14. The portions 24 and 25 bear against the inner face of the

35 portions 13 and 14 in one case, and in the other case against the outer face of the portions 47 and 48, and the portions corresponding to the portions 24 and 25 against the inner face of the portions 47 and 48. To se-

40 cure the cap in this position I have provided in each case upper and lower tongue extensions 26 and 27 which are bent inward so as to bear against the upper and lower edges of the portions 13 and 14 of the tongue il-

lustrated in Fig. 4, and against the upper 45 and lower edges of the portions 47 and 48 in the construction illustrated in Fig. 8. By this means, a head is formed fitting within the channel bar 8, as clearly indicated in Figs. 1 and 6, or in the channel piece 42 50 indicated in Fig. 7, the locking tongue being then forced downward so that the body 12 of the tongue, referring to Figs. 4, 5 and 6 adjacent to the portion 12 and 13, and formed by the portions 12^x and 12° enters 55 the slotted extension 10 between the head above described and the outwardly flanged portions 16 and 17; or, referring to Figs. 7 and 8, the portions 47 and 48 are forced into the slit opening 44.

60 From this description it will be seen that I have devised a very simple form of locking tongue which may be cheaply made and will at the same time be strong and durable, and an efficient form of lock.

What I claim as my invention is: The combination with two wall members set at right angles one to the other, of a channel piece secured to one member and having a vertical slit located in the wall forming the base 70 of the channel, a locking tongue comprising a strip of metal, the body of which is bent intermediately upon itself to form a double thickness adapted to fit into the aforesaid slit of the channel member, and having its 75 ends out-turned and the edges of the out-turned portion converging from one end thereof to the other, and a securing cap having its sides converging from one end to the other and inturned to conform to the shape 80 of the aforementioned out-turned portions of the body and then inwardly with the inner side of such out-turned portions and having upwardly and downwardly extending tongue extensions adapted to be bent inward 85 to engage the out-turned portions of the body.

CHARLES PETER CAMPBELL.
